15 Claims. (Cl. 158—4)

The present invention relates to apparatus for heating fluids, such as water or air, and more particularly to an improved pulse jet burner which may be used in such apparatus as a means for generating heat energy.

Water and air heaters which comprise one or more pulse jet burners (also called resonance duct burners) are known in the art. Such burners must be absolutely airtight to prevent escape of combustion products into the surrounding atmosphere. Furthermore, it is equally important to reduce the noise to a bearable level so that a heater embodying one or more pulse jet burners may be used in homes without being a source of irritation to the occupants. It must be borne in mind that a pulse jet burner operates at elevated pressures and that, in the absence of any soundproofing, the noise might reach an undesirable level. Heretofore, the noise was combatted by large quantities of expensive sound absorbing material but, to my knowledge, the results obtainable with such material were quite unsatisfactory.

Accordingly, it is an important object of my invention to provide an improved pulse jet burner which is constructed and assembled in such a way that the noise produced on combustion of a fuel-oxygen mixture is reduced to a level which is very satisfactory to warrant the use of such burners in private homes, and wherein such substantial reduction in noise is achieved with minimal quantities of sound absorbing material.

Another object of the invention is to provide a pulse jet burner of the just outlined characteristics which is constructed and assembled with a view to prevent escape of any noxious gases into the surrounding atmosphere, which is of very compact and space-saving design, which may be used in room heating and/or water heating systems, and wherein each noise-generating element or component is shielded by at least one silencer.

A further object of the invention is to provide a novel soundproofing or silencing arrangement for the combustion chamber and for the resonance duct of a pulse jet burner.

With the above objects in view, one feature of my invention resides in the provision of a fluid heating apparatus which comprises a pulse jet burner and heating pipe means arranged to convey fluid to be heated into an inner soundproofing space so that the fluid may exchange heat with one or more combustion chambers which are accommodated in the soundproofing space. The pulse jet burner comprises an outer shell which defines an outer soundproofing space, an inner shell which is surrounded by the outer soundproofing space and which defines the inner soundproofing space, at least one combustion chamber mounted in the inner shell so as to be at least partially surrounded by the inner soundproofing space, suction duct means arranged to deliver a mixture of oxygen and fuel into the combustion chamber so that the mixture is combusted and heats the chamber when the burner is in operation, and resonance duct means arranged to convey from the combustion chamber spent gases which develop on combustion of the mixture. The outer shell has an inlet which admits oxygen or oxygen-containing air into the outer soundproofing space, and the inner shell is provided with port means through which oxygen or oxygen-containing air is drawn into the inner soundproofing space to enter the open intake of the suction duct means and to

2

be mixed with fuel which is delivered by a supply conduit extending through the shells and into the inner soundproofing space.

The novel features which are considered as characteristic of the invention are set forth in particular in the appended claims. The improved pulse jet burner itself, however, both as to its construction and its method of operation, together with additional features and advantages thereof, will be best understood upon perusal of the following detailed description of certain specific embodiments with reference to the accompanying drawings, in which:

FIG. 1 is a central vertical section through a fluid heating apparatus including a pulse jet burner which embodies one form of my invention;

FIG. 1a is a fragmentary central vertical section through a slightly modified pulse jet burner;

FIG. 2 is a horizontal section as seen in the direction of arrows from the line II—II of FIG. 1 and illustrates the upper portion of a two-piece partition which is located below the discharge end of the resonance duct;

FIG. 3 is a horizontal section as seen in the direction of arrows from the line III—III of FIG. 1 and illustrates the lower portion of this partition;

FIG. 4 is a horizontal section as seen in the direction of arrows from the line IV—IV of FIG. 1 and illustrates the construction of the lowermost part of the inner shell; and

FIG. 5 is a perspective view of the lower portion of the inner shell with the cylindrical wall partially broken away.

Referring to the drawings, and first to FIG. 1, there is shown a fluid heating apparatus including a pulse jet or resonance duct burner whose combustion chamber 10 serves to heat a continuous stream of fluid (e.g., water or air) which is conveyed through a delivery pipe 25. The fluid flows through a heating pipe 27 which is coiled around the combustion chamber 10 and the thus heated fluid is thereupon led away through an evacuating pipe 26.

While flowing through the convoluted heating pipe 27, the fluid exchanges heat with the wall of the chamber 10 which is heated on explosion of gaseous or pulverulent fuel admitted through a supply conduit 13. This supply conduit 13 discharges into a suction duct 11 which communicates with the upper end of the chamber 10 and whose open intake sucks oxygen or oxygen-containing air from an upper compartment 14 defined by the upper portion of an inner housing or shell 15 when the burner is in operation. In accordance with one feature of my invention, the combustion chamber 10 is accommodated in the compartment 14 and is spaced from the walls of the inner shell 15. The latter is provided with a first sealed opening 23 for the supply conduit 13 and with two additional sealed openings 24, 24a for the pipes 25, 26. The combustible mixture which is formed in the suction duct 11 enters the interior of the combustion chamber 10 and is exploded in rapid sequence. Following each explosion, a sound wave and a column of spent gas will travel down a tail pipe or resonance duct 12 which extends through

a sealed opening 29 provided in a horizontal partition 21 located in a plane which is perpendicular to the axis of the inner shell 15 and serving to separate the upper compartment 14 from a lower compartment 20. The operation of the pulse jet burner is well known in the art and by itself forms no part of my invention.

The upper compartment 14 in the inner shell 15 constitutes a first soundproofing or silencing space of the improved pulse jet burner, and this space is surrounded by a second soundproofing or silencing space 19 defined by an outer housing or shell 16 which surrounds the inner shell. In the embodiment of FIG. 1, the inner shell 15 assumes the form of an upright cylinder whose walls are spaced

70

from the walls of the outer shell 16 so that the outer soundproofing space 19 surrounds the entire inner shell. As shown, the interior of the inner shell 15 accommodates not only the combustion chamber 10 but also the convoluted heating pipe 27, the suction duct 11, a portion of the supply conduit 13, and the resonance duct 12. The open end of the resonance duct 12 discharges into the lower compartment 20 whence the spent gas advances into a take-off pipe 28 in a manner to be described in connection with FIGS. 2 to 5.

The outer shell 16 comprises a cupped front section 17 which is detachably but sealingly secured to a pan-shaped rear section 18 by an elastic coupling 30 disposed in a vertical plane and serving to permit expansion or contraction of the outer shell depending on the momentary pressure in the outer shell soundproofing space 19. Thus, and if the pressure in the space 19 rises, the mixture of fuel and air cannot escape from the outer shell 16 because the coupling 30 expands. The sealing action may be provided by an annular gasket 30a.

The just described construction of the outer shell 16 is of particular importance when the burner is started or when the operation of the burner is not entirely satisfactory. For example, and if it should happen that the supply conduit 13 develops a leak, a combustible mixture of fuel and oxygen will penetrate into the outer soundproofing space 19 and might even explode to send a column of spent gas into the surrounding atmosphere. Such gas could escape through the inlet 31 were it not for the feature that the outer shell 16 may expand to compensate for variations in pressure prevailing in the space 19. The same result can be achieved by mounting the gasket 30a in such a way that it opens a path for escape of fluid into the surrounding atmosphere when the pressure prevailing in the space 19 reaches an undesirably high magnitude.

The material of the shells 15, 16 may be comparatively thin to reduce the cost and the weight of the burner.

The interior of the inner shell 15 actually forms several distinct soundproofing or silencing spaces one of which (the upper compartment 14) absorbs noise which develops when the mixture of fuel and air is drawn into and through the suction duct 11 and the other of which (the lower compartment 20) absorbs noise which develops when columns of spent gas are discharged through the resonance duct 12. It was found that such construction of the pulse jet burner, especially in combination with the outer shell 16, reduces noise sufficiently to warrant the utilization of such burners in the water-heating and room-heating systems of one-, two- or multi-family dwellings.

In the structure of FIG. 1, the partition 21 is located at a level slightly below the discharge opening of the combustion chamber 10, i.e., somewhat below the intake end of the resonance duct 12. In accordance with a slight modification of my invention which is shown in FIG. 1a, the partition 21' may be coplanar with the bottom wall of the combustion chamber 10' so that the entire resonance duct 12' is located in the lower compartment 20'. The lowermost convolution of the heating pipe 27' extends substantially diametrically across the interior of the combustion chamber 10' so that the fluid flowing through the evacuating pipe 26' is heated to a very high temperature. Such heating is enhanced by fins or ribs 27a' provided on the lowermost convolution of the pipe 27'.

The compartment 14 communicates with the space 19 through a connecting port 22 which is provided in the top wall of the inner shell 15, and the rear section 18 of the outer shell 16 is formed with an air-admitting inlet 31 which delivers air into the space 19 whence the air may flow into the compartment 14 via port 22 to enter the open intake of the suction duct 11. The rear section 18 of the outer shell 16 is further formed with a first sealed opening 32 for the supply conduit 13, with a pair of sealed openings 34, 34a for the pipes 25, 26, and with a fourth sealed opening 33 for the take-off pipe 28.

It will be noted that spent gas discharged by the reso-

nance duct 12 cannot flow directly into the take-off pipe 28. This is due to the fact that the improved burner comprises a further soundproofing compartment or space 55 in the lowermost part of the inner shell 15 which is sealed from the compartment 20 by a horizontal partition 35 whose component parts are illustrated in FIGS. 2 and 3. The partition 35 defines an annular channel 36 which conveys spent gas into an annular soundproofing space 37 extending between the partition 35 and the bottom wall of the inner shell 15. The lower portion of this annular space 37 communicates with the intake end of the take-off pipe 28 which extends through the bottom wall of the inner shell 15, through the lower part of the space 19 and through the sealed opening 33.

The partition 35 comprises an upper disk-shaped portion 41 which is shown in FIG. 2 and whose underside is provided with an annular depression or groove 43 of semicircular cross section. The portion 41 is formed with one or more apertures 46 enabling spent gas to flow from the compartment 20 into the channel 36. The lower disk-shaped portion 42 of the partition 35 is illustrated in FIG. 3, and the upper side of this lower portion is provided with an annular depression or groove 44 which registers with the groove 43 so that the two grooves together form the aforementioned annular channel 36 which is of circular cross section. The second portion 42 is further provided with one or more apertures 47 permitting spent gas to flow into the annular space 37. The apertures 46, 47 shown in FIGS. 2 and 3 are staggered with reference to each other and are separated by an upright baffle 45 which compels spent gas entering at 46 to flow through the major part of the channel 36 prior to passing through the aperture 47 and into the annular space 37. In other words, spent gas must travel in an arc of nearly 360 degrees prior to escaping through the aperture 47 and into the lowermost compartment 55 of the inner shell 15. It goes without saying that the aperture 46 or 47 may be replaced by two or more smaller apertures which may be spaced from each other in the longitudinal direction of the channel 36. The distance between the apertures 46, 47 will determine the color of the sound which is being produced by spent gas.

The aperture 47 is located at a level above an enlarged portion 49 of the space 36 (see FIGS. 4 and 5) whose major portion 49 is bounded by two bodies of suitable sound absorbing material including a solid cylindrical inner body 51 and a hollow cylindrical outer body 51a. The space 37 further comprises a second enlarged portion 50 which extends upwardly from the intake end of the take-off pipe 28. The inner and outer sides of the entire annular space 37 are bounded by perforated metallic sheets 54 best shown in FIG. 5. The noise produced by spent gas discharged from the resonance duct 12 is reduced to acceptable level while the gas must pass through the aperture 46 into the channel 36, thereupon into the annular space 37 via aperture 47, and finally into and through the take-off pipe 28.

The supply conduit 13 comprises two enlarged portions 52 and 53 one of which is outwardly adjacent to the outer shell 16 and the other of which is located in the compartment 14 close to the section duct 11. The enlarged portions 52, 53 and the intermediate portion 13a between these enlarged portions define a further soundproofing or silencing space.

If it should happen that the inner shell 15 develops a leak in the region of the lower compartment 20, spent gas might penetrate into the outer space 19 but it thereupon sucked through the connecting port 22 to enter the upper compartment 14 and to be admitted into the combustion chamber 10. Thus, even if such a leak should develop, spent gas is still prevented from entering the atmosphere around the outer shell 16 of the burner. As long as the leak is small, spent gas returned into the suction pipe 11 will have little effect on the combustion; however, if the leak is substantial, the fuel-air mixture

might not contain enough oxygen and the combustion of such mixture is then terminated in a fully automatic way.

The situation is the same if a leak develops in the wall of the combustion chamber. The gases escape into the compartment 14 and are sucked through the open intake of the duct 11. The operation of the burner will be brought to a standstill if the leak in the combustion chamber is large enough to reduce the percentage of oxygen in the combustible mixture below a minimum value.

It goes without saying that the inner shell 16 may accommodate two or more combustion chambers and an equal number of suction ducts and resonance ducts without in any way departing from the spirit of my invention. A twin combustion chamber which may be used in the pulse jet burner of the present invention is disclosed in my copending application Serial No. 212,048, filed July 24, 1962, to which reference may be had if necessary.

The sound absorbing spaces defined by the shells 15 and 16 reduce the noise to an acceptable level even though the improved pulse jet burner utilizes very small quantities of sound absorbing material. The use of such material may be restricted solely to the third compartment 55 in the lowermost zone of the inner shell 15 which means that the weight of the burner is rather small.

The compartment 14 and the surrounding portion of the outer soundproofing space 19 will form an effective barrier to the noise which develops in the combustion chamber 10, in the suction duct 11 and in the supply conduit 13. The same applies to the silencing action of the compartments 20, 55 and the lower portion of the space 19 which will reduce noise produced by spent gases in the duct 12, channel 36 and annular space 37. The provision of the soundproofing space defined by the enlarged portions 52, 53 and intermediate portion 13a of the supply conduit 13 is an additional feature of my invention.

The composition of sound absorbing bodies 51, 51a may be made out of slag or mineral wool or the like.

Without further analysis, the foregoing will so fully reveal the gist of the present invention that others can, by applying current knowledge, readily adapt it for various applications without omitting features that, from the standpoint of prior art, fairly constitute essential characteristics of the generic and specific aspects of this invention and, therefore, such adaptations should and are intended to be comprehended within the meaning and range of equivalence of the following claims.

What is claimed as new and desired to be secured by Letters Patent is:

1. In a pulse jet burner, in combination, a shell defining a closed soundproofing space; port means in said shell forming an inlet for an oxygen-containing gaseous medium into said soundproofing space; a combustion chamber arranged entirely within said soundproofing space so that combustion gases possibly escaping from said combustion chamber through a leak therein will enter said soundproofing space; a suction duct connected at one end to said combustion chamber, said suction duct passing through said soundproofing space and through said shell so that it inlet end which is adapted to receive fuel is located outside of said shell, said suction duct having intake opening means located within said soundproofing space in said shell to receive not only oxygen-containing gaseous medium entering said soundproofing space through said port means, but also to reconvey into said combustion chamber any combustible gases which might have escaped from said combustion chamber into said soundproofing space; and a resonance duct connected to said combustion chamber and passing through said shell so as to convey spent gases from said combustion chamber to the outside of said shell.

2. A combination as set forth in claim 1, wherein said intake opening means of said suction duct located within

said soundproofing space in said shell is spaced from said port means in said shell.

3. A combination as set forth in claim 1, further comprising heating pipe means having a portion located in said soundproofing space in heat exchanging relationship with said combustion chamber and arranged to convey fluid to be heated through said space so that the fluid may exchange heat with said combustion chamber.

4. A combination as set forth in claim 3, wherein said suction duct comprises a first enlarged portion located externally of said outer shell, a second enlarged portion located in said soundproofing space, and a connecting portion extending between said enlarged portions, said portions of said suction duct together defining a second soundproofing space.

5. In a pulse jet burner, in combination, an outer shell defining an outer soundproofing space; an inner shell accommodated in said outer soundproofing space and defining a closed inner soundproofing space; port means in said inner shell forming an inlet for an oxygen-containing gaseous medium into said inner soundproofing space; a combustion chamber arranged entirely within said inner soundproofing space so that combustion gases possibly escaping from said combustion chamber through a leak therein will enter said inner soundproofing space; a suction duct connected at one end to said combustion chamber, said suction duct passing through said inner soundproofing space and through said inner shell so that its inlet end which is adapted to receive fuel is located outside of said inner shell, said suction duct having intake opening means located within said inner soundproofing space in said inner shell to receive not only oxygen-containing gaseous medium entering said inner soundproofing space through said port means, but also to reconvey into said combustion chamber any combustible gases which might have escaped from said combustion chamber into said inner soundproofing space; and a resonance duct connected to said combustion chamber and passing through said inner shell so as to convey spent gases from said combustion chamber.

6. In a pulse jet burner, in combination, an outer shell defining a closed outer soundproofing space; an inner shell accommodated in said outer soundproofing space and defining a second closed soundproofing space, said inner and said outer shells comprising walls which are spaced from each other so that said inner shell is completely surrounded by said outer soundproofing space; first port means in said outer shell forming an inlet for an oxygen-containing gaseous medium into said outer soundproofing space; second port means in said inner shell forming an inlet for said medium from said outer space into said inner soundproofing space; a combustion chamber arranged entirely within said inner soundproofing space so that combustion gases possibly escaping from said combustion chamber through a leak therein will enter said inner soundproofing space; a suction duct connected at one end to said combustion chamber and passing through said inner and outer shells so that its inlet end which is adapted to receive fuel is located outside of said outer shell, said suction duct having inlet opening means located within said inner soundproofing space to receive not only oxygen-containing gaseous medium entering said inner soundproofing space through said second port means, but also to reconvey into said combustion chamber any combustible gases which might have escaped from said combustion chamber into said inner soundproofing space; and a resonance duct connected to said combustion chamber and passing through said inner and outer shells so as to convey spent gases from said combustion chamber to the outside of said outer shell.

7. In a pulse jet burner, in combination, an outer shell defining a closed outer soundproofing space; an inner shell defining a closed inner soundproofing space accommodated in said outer soundproofing space and comprising an internal partition which divides said inner space into a pair of compartments; first port means in

7
said outer shell forming an inlet for an oxygen-containing gaseous medium into said outer soundproofing space; second port means in said inner shell forming an inlet for said medium from said outer space into one of said compartments; a combustion chamber arranged entirely within said one compartment in said inner soundproofing space so that combustion gases possibly escaping from said combustion chamber through a leak therein will enter said one compartment; a suction duct connected at one end to said combustion chamber, said suction duct passing through said one compartment and through said inner and outer shells so that its inlet end which is adapted to receive fuel is located outside of said outer shell, said suction duct having an intake opening located within said one compartment and adapted to receive not only oxygen-containing gaseous medium entering said one compartment through said second port means, but also to reconvey into said combustion chamber any combustible gases which might have escaped from said combustion chamber into said one compartment; a resonance duct connected to said combustion chamber and sealingly extending through said partition, said resonance duct having an open end arranged to discharge into said other compartment spent gases from said combustion chamber; and a take-off pipe connected with said inner shell and communicating with said other compartment and extending through said outer soundproofing space and through said outer shell to evacuate spent gases from said other compartment to the outside of said outer shell.

8. A combination as set forth in claim 7, wherein said second port means is spaced from said first port means so that combustion gases possibly leaking into said outer soundproofing space from said inner soundproofing space or from that portion of said take-off pipe which passes through said outer soundproofing space will enter said one compartment through said second port means to be reconveyed through said intake opening into said combustion chamber.

9. In a pulse jet burner, in combination, a shell defining a closed soundproofing space and comprising an internal partition which divides said space into a pair of compartments, said shell further having port means communicating with one of said compartments and forming an inlet for an oxygen-containing gaseous medium into said one compartment; a combustion chamber arranged entirely within said one compartment so that combustion gases possibly escaping from said combustion chamber through a leak therein will enter said one compartment; a suction duct connected at one end to said combustion chamber, said suction duct passing through said one compartment and through said shell so that its inlet end which is adapted to receive fuel is located outside of said shell, said suction duct having an intake opening located within said one compartment in such a manner as to be adapted to receive not only oxygen-containing gaseous medium entering said one compartment through said port means, but also to reconvey into said combustion chamber any combustible gases which might have escaped from said combustion chamber into said one compartment; a resonance duct connected to said combustion chamber and sealingly extending through said partition, said resonance duct having an open end arranged to discharge into said other compartment spent gases from said combustion chamber; and a take-off pipe connected from said shell and arranged to evacuate spent gases from said other compartment.

10. In a pulse jet burner, in combination, a shell defining a closed soundproofing space and comprising a first internal partition and an apertured second internal partition, said partitions dividing said soundproofing space into three compartments including a first compartment locat-

ed at one side of said first partition, a second compartment located between the other side of said first partition and one side of said second partition, and a third compartment located at the other side of said second partition; port means in said shell forming an inlet for an oxygen-containing gaseous medium into said first compartment; a combustion chamber arranged entirely within said first compartment so that combustion gases possibly escaping from said combustion chamber through a leak therein will enter said first compartment; a suction duct connected at one end to said combustion chamber, said suction duct passing through said first compartment and through said shell so that its inlet end which is adapted to receive fuel is located outside of said shell, said suction duct having an intake opening located within said first compartment in said shell in such a manner as to be adapted to receive not only oxygen-containing gaseous medium entering said first compartment through said port means but also to reconvey into said combustion chamber any combustible gases which might have escaped from said combustion chamber into said first compartment; a resonance duct connected to said combustion chamber and passing through said first internal partition so as to convey spent gases from said combustion chamber to said second compartment; and take-off pipe means communicating with said third compartment to evacuate therefrom spent gases which pass into said first compartment via said apertured second internal partition.

11. A combination as set forth in claim 10, wherein said second partition defines an annular channel and wherein said third compartment includes first and second apertures communicatingly connecting said channel with said second and third compartments respectively.

12. A combination as set forth in claim 10, wherein said shell is cylindrical in shape and wherein said partitions are located in planes which are perpendicular to the axis of said shell.

13. A combination as set forth in claim 11, further comprising baffle means mounted in said second partition and extending into said channel for restricting circulation of spent gas in said channel, said first and second apertures being located at the opposite sides of said baffle means so that spent gases entering one of said apertures must flow through a substantial portion of said channel prior to reaching the other aperture.

14. A combination as set forth in claim 11, further comprising bodies of sound absorbing material provided in said third compartment and defining an annular soundproofing space which communicates with said channel via one of said apertures and with said take-off pipe means.

15. A combination as set forth in claim 14, wherein said annular soundproofing space includes a first enlarged portion adjacent to said one aperture and a second enlarged portion adjacent to said take-off pipe means.
